(57) **CLAIM**

The ornamental design for a container closure, as shown and
described.

DESCRIPTION

FIG. 1 is a perspective view of a container closure showing
our new design;

FIG. 2 is a front view thereof;

FIG. 3 is a right side view thereof;

FIG. 4 is a rear view thereof;

FIG. 5 is a top view thereof;

FIG. 6 is a left side view thereof; and,

FIG. 7 is a bottom view thereof.

In the drawings, the broken lines showing portions of a
container closure depict environment and form no part of the
claim.
